CLAIM

The ornamental design for an off-trigger locator attachment, as shown and described.

DESCRIPTION

FIG. 1 is a front view of the off-trigger locator attachment for a firearm;

FIG. 2 is a top view of the off-trigger locator attachment of FIG. 1;

FIG. 3 is a left side view of the off-trigger locator attachment of FIG. 1;

FIG. 4 is a right side view of the off-trigger locator attachment of FIG. 1;

FIG. 5 is rear view of the off-trigger locator attachment of FIG. 1 (opposite the view of FIG. 1);

FIG. 6 is bottom view of the off-trigger locator attachment of FIG. 1 (opposite the view of FIG. 2);

FIG. 7 is a perspective view of the off-trigger locator attachment of FIG. 1;

FIG. 8 is an alternate perspective view of the off-trigger locator attachment of FIG. 1;

FIG. 9 is a front view of the off-trigger locator attachment of FIG. 1 shown mounted to an exemplary firearm (shown in phantom) to illustrate the environment in which the off-trigger locator attachment is used;

FIG. 10 is a front view of an alternate embodiment of the off-trigger locator attachment for a firearm;

FIG. 11 is a top view of the off-trigger locator attachment of FIG. 10;

FIG. 12 is a right side view of the off-trigger locator attachment of FIG. 10;

FIG. 13 is a left side view of the off-trigger locator attachment of FIG. 10;

FIG. 14 is rear view of the off-trigger locator attachment of FIG. 10 (opposite the view of FIG. 10);

FIG. 15 is bottom view of the off-trigger locator attachment of FIG. 10 (opposite the view of FIG. 11);

FIG. 16 is a perspective view of the off-trigger locator attachment of FIG. 10;

FIG. 17 is an alternate perspective view of the off-trigger locator attachment of FIG. 10; and,

FIG. 18 is a front view of the off-trigger locator attachment of FIG. 10 shown mounted to an exemplary firearm (shown in phantom) to illustrate the environment in which the off-trigger locator attachment is used.

The dashed lines form no part of the claimed design.
